UNITED STATES PATENT OFFICE.

LARKIN J. MEAD, OF AURORA, ILLINOIS, ASSIGNOR TO AURORA CORSET COMPANY,
OF AURORA, ILLINOIS, A CORPORATION OF ILLINOIS.

COMBINATION CORSET AND BRASSIÈRE.

Application filed July 25, 1927. Serial No. 208,273.

This invention relates to improvements in combination corset and brassières.

The object of the invention is to provide a combination garment which is adapted to 5 properly confine the figure of the wearer both above and below the waist line; a garment in which the corset and the brassière portions are laterally adjustable independently of each other to accommodate figures 10 of varied proportions, and in which the corset and brassière portions overlap in a manner to produce straight, unbroken lines at the back and front of the garment.

In the drawings:

15 Figure 1 is a perspective view showing the garment in position upon a wearer.
Figure 2 is a back view of the garment.
Figure 3 is an enlarged fragmentary view of a detail.
20 In that embodiment of my invention which I have chosen to illustrate and describe herein, the combination garment comprises a corset A and brassière B, connected together only at the sides, slightly toward 25 the back, in overlapping relation.

The corset A consists of two non-elastic front sections 1 and 2, two non-elastic back sections 3 and 4, and elastic side members 5 and 6, which are between the front and back sections and stitched thereto. The elastic sides 5 and 6 are reinforced near the bottom by superposed elastic strips 7 and 8, respectively, extending at an angle to the woof of the sides 5 and 6. The strips 7 and 8 are stitched to the corset only at their ends, and hold the corset down on the figure. The corset is preferably side-opening, the front 2 and side 6 being provided with the usual hooks and eyes, respectively, at their proximate edges.

The front sections 1 and 2 are adjustably connected together by laces 9 and the back sections 3 and 4 by laces 10, which are inserted through eyelets in the parts mentioned in a familiar manner. Boning 11 is provided for the back and front of the corset.

The front sections 1, 2, and the sides 5, 6, are adapted to cover the abdomen and sides of the hips and to extend upwardly to or 50 slightly above the normal waistline. The

back sections 3 and 4 are longer than the front and sides and extend above the normal waist line to a slightly greater degree.

Referring now to the brassière B, it will be seen that the same comprises a front 12 which 55 is adapted to cover the front of the bust of the wearer and extends downwardly to form an apron 12', which overlies the front of the corset A. The back of the brassière B comprises two non-elastic portions 13 and 14 and 60 an elastic strip 15 between them and connected thereto. 16 and 17 indicate the sides which may be integral with the front 12 or with the back members 14 and 13, respectively, or the parts may be separate and 65 stitched together. The brassière has the usual shoulder straps 18, and the apron 12' and lower margin of the corset A are provided with garters 19. Boning for the brassière is indicated at 20. The brassière is preferably 70 side-opening at the center of the side 16, and provided with the usual hooks and eyes.

Attention is called to the fact that in combining the corset A and brassière B, the front and sides of the brassière comprising the parts 75 12, 16 and 17 are arranged to overlie the parts 1, 2, 5 and 6 of the corset A, so that the apron 12' extends over the parts 1 and 2, and the lower margin 21 of the sides of the brassière is in a lower horizontal plane than the margin 80 22 of the corset when the garment is in position. On the other hand, at the back of the garment, the tops of the corset sections 3 and 4 are arranged to overlie a portion of the brassière sections 13, 14 and 15, so that the 85 upper margin 23 of the back of the corset is in a higher horizontal plane than the margin 24 of the brassière, when the garment is being worn.

It will also be noted that the two parts A 90 and B are independent and not connected together excepting at the sides, slightly toward the back, by longitudinal lines of stitches indicated at 25. (See Figure 3.) These are the same stitches which connect together the 95 parts 13 and 17, 14 and 16, 4 and 6, and 3 and 5, and hold together the overlapped portions of 16, 14, 6 and 4 on one side, and 17, 13, 5 and 3 on the other side.

The brassière may be fitted to the figure of 100

the wearer, a desirable degree of adjustability being permitted by the elastic 15; and the corset portion A may be adjusted both at the back and front without limitation on account of the brassière construction or its connection to the corset A. The connecting together of the two garments at the sides only and by longitudinally arranged lines of stitches provides the greatest possible opportunity for independent lateral adjustment without disturbing the proper fit of either garment. If the margins 23 were stitched to the parts 13 and 14, and the boning 11 and 20 integral, the loosening of the laces 10 to any appreciable extent would result in a distortion of the boning and detract from the comfort of the garment. As stated, by my construction, I provide an unusual opportunity for adjustment. The superposing of the brassière upon the corset at the front and sides and the superposing of the corset upon the brassière at the back is a feature of construction which is of importance in maintaining smooth, unbroken lines and keeping the two parts in proper relative position upon the wearer.

I claim as my invention:

A combination garment comprising a corset and a brassière, the corset having non-elastic back sections connected together by lacings, a non-elastic front section connected to said back sections by intermediate elastic side members, the brassière comprising an elastic back section and non-elastic front and side sections connected together, the non-elastic back sections of the corset extending upwardly above the waist line of the wearer and overlying the back of the brassière, the sides and front of the brassière overlapping the sides and front of the corset, the lower margin of the sides of the brassière being in a horizontal plane below the upper edge of the corset back when in position upon the body of the wearer, the proximate margins of the corset and brassière sections being free from each other, said sections being connected together only at the longitudinal margins of the back section where they overlie the brassière.

50 In testimony that I claim the foregoing as my invention I affix my signature this 13th day of July, 1927.

LARKIN J. MEAD.
